UNITED STATES PATENT OFFICE.

ROBERT LYGERTWOOD ESSON, OF JOHANNESBURG, TRANSVAAL, SOUTH AFRICA.

LOOSE-LEAF BINDER AND THE LIKE.

1,426,468.

Specification of Letters Patent. Patented Aug. 22, 1922.

Application filed September 3, 1921. Serial No. 498,211.

To all whom it may concern:

Be it known that I, ROBERT LYGERTWOOD ESSON, a subject of the King of Great Britain, and resident of Johannesburg, Transvaal Province, Union of South Africa, have invented certain new and useful Improvements Appertaining to Loose-Leaf Binders and the like, of which the following is a specification.

10 This invention appertains to loose-leaf binders, loose-leaf ledgers and the like.

It has been more especially designed for use with that type of binder in which the means or mechanism for contracting and expanding the back of the binder includes a rod or spindle having right and left-hand threaded portions, on which are mounted nuts which are caused to travel along the rod or spindle when the latter is rotated by 15 a key. It can, however, be used with other binders in which a rotatable rod or spindle is employed for actuating the adjusting mechanism.

The present improvements relate to the 20 construction of the key and that portion of the rod or spindle with which it engages.

The object of the invention is to improve the construction of the key and the means whereby it co-operates with the rod or 25 spindle, to ensure that the key shall effectively engage the end thereof, and to provide a strong and durable key of simple and inexpensive construction.

The invention will be fully described in 30 connection with the accompanying drawings, wherein—

Fig. 1 is an elevation of the key.

Fig. 2 is a plan view of the same.

Fig. 3 an end elevation, and

40 Fig. 4 a view of portion of the end of the rod or spindle with which the key co-operates.

In the construction of the key I employ a barrel or main portion 1 which is of 45 hollow or tubular construction for a portion of its length, as indicated at 2, and is adapted to engage with or be projected over the end of the rod or spindle 3—see Fig. 4.

In the barrel portion 1 and near the outer 50 end thereof, there is formed a slot 4 of suitable width and length. The barrel 1, in its rear portion, may be fashioned with a flat 5, and at the rear end of the flat with a recess 6. Upon the barrel 1 there is arranged 55 a suitably shaped spring piece 7, which at its forward end is formed with a projection

8 which projects through the slot 4, formed in the front portion of the barrel 1, and enters the interior of the barrel. This projection 8 may be of any suitable shape, being 60 preferably rounded or curved on the inner face in a direction longitudinally of the barrel, as shown. The rear portion of the spring piece 7 lies on the flat 5, and the rear end is bent to fit into the recess 6, formed 65 at the rear of the flat 5, in which recess it is fixed.

Near the end of the rod or spindle 3, there is formed a longitudinal groove 9, which may, as shown, be curved at the bottom to 70 correspond, more or less, to the curvature of the projection 8, on the spring piece 7. By rounding or curving the projection 8, and the groove 9, the former falls into and engages the latter when the barrel is pushed 75 over the end of the rod or spindle. The projection 8 is firmly held in engagement with the groove 9, by the action of the spring of the spring piece 7, and the key can be then turned to rotate the rod or 80 spindle. In pulling the key off the rod or spindle, the curved projection 8 will ride up the curved bottom of the groove 9 against the force of the spring, and so disengage the slot 4. 85

At the rear end of the barrel portion 1, a handle or means is provided for rotating the key. Such means may, as shown, be in the form of a thumb or wing piece 10, fitted into a recess or groove 11 in the end of 90 part 1, and secured to the barrel 1 by means of rivet or pin 12. The handle 10 may be recessed as shown at 13 to project over the rear end of the spring piece 7, and serve as a means for securing the end of said piece 95 in the recess 6. It will be evident that the handle may be formed integral with the barrel and that it may be in the form of a crank handle or be otherwise shaped, as preferred; and that the spring piece could be 100 retained in operative position in any other preferred manner.

What I claim as my invention, and desire to protect by Letters Patent is:—

1. In loose-leaf binders, a key comprising 105 a portion which is adapted to fit over the end of the rod or spindle of the adjusting mechanism, and a spring-actuated piece which is yieldingly carried by said portion and is adapted to engage with that part of 110 the rod or spindle over which said portion fits.

2. In loose-leaf binders, a key comprising a portion which is adapted to fit over the end of the rod or spindle of the adjusting mechanism, and a spring-actuated piece which is yieldingly carried by said portion and is adapted to engage with that part of the rod or spindle over which said portion fits, said spring-actuated piece being provided with a longitudinally curved or rounded projection, on the inside, to fit a correspondingly shaped groove in the end of the rod or spindle of the adjusting mechanism.
3. In loose-leaf binders, a key comprising a portion which is adapted to fit over the end of the rod or spindle of the adjusting mechanism, and a spring piece which is yieldingly carried by said portion and is adapted to engage with that part of the rod or spindle over which said portion fits, said spring piece including a projection constructed integral with the spring part, which latter is fixed at its rear end to the rear portion of the key.
4. In loose-leaf binders, a key comprising a portion which is adapted to fit over the end of the rod or spindle of the adjusting mechanism, and a spring-actuated piece which is yieldingly carried by said portion and is adapted to engage with that part of the rod or spindle over which said portion fits, said spring-actuated piece being pro-

vided with a longitudinal projection on the inside, to fit a correspondingly shaped groove in the end of the rod or spindle of the adjusting mechanism, the barrel portion of the key being constructed with a longitudinal slot for the projection on the spring-actuated piece.

5. In loose-leaf binders, a key comprising a portion which is adapted to fit over the end of the rod or spindle of the adjusting mechanism, and a spring-actuated piece which is yieldingly carried by said portion and is adapted to engage with that part of the rod or spindle over which said portion fits, said spring-actuated piece being provided with a longitudinal projection on the inside, to fit a correspondingly shaped groove in the end of the rod or spindle of the adjusting mechanism, the barrel portion of the key being constructed with a longitudinal slot for the projection on the spring-actuated piece, and with a recess to receive the rear end of the spring piece, so that the latter is retained in position by means of the handle.

In testimony whereof I have signed my name to this specification in the presence of two subscribing witnesses.

ROBERT LYGERTWOOD ESSON.
